VENDING DEVICE

Curtis G. Jones, 7418 Fenlon Drive,
Dallas, Tex. 75231

Filed Mar. 18, 1966, Ser. No. 1,532

Term of patent 14 years

(Cl. D52—3)

Fig. 1

Fig. 2

Fig. 3

Fig. 4

FIGURE 1 is a front elevational view of a vending device embodying my new design.

FIGURE 2 is a rear elevational view thereof.

FIGURE 3 is a top plan view, and

FIGURE 4 is a bottom plan view.

The showing of the gum balls in broken lines is for illustrative purposes only.

I claim:

The ornamental design for a vending device, as shown and described.
